UNITED STATES PATENT OFFICE.

DAVID J. JENNINGS, OF CLEVELAND, OHIO.

AUTOMATIC MACHINE FOR THE MANUFACTURE OF PAPER RECEPTACLES.

1,276,535.

Specification of Letters Patent. Patented Aug. 20, 1918.

Application filed March 20, 1915. Serial No. 15,811.

To all whom it may concern:

Be it known that I, DAVID J. JENNINGS, a citizen of the United States, residing at Cleveland, in the county of Cuyahoga and 5 State of Ohio, have invented certain new and useful Improvements in Automatic Machines for the Manufacture of Paper Receptacles; and I do hereby declare the following to be a full, clear, and exact description 10 of the invention, such as will enable others skilled in the art to which it pertains to make and use the same.

This invention relates to machines for the manufacture of bodies for paper receptacles 15 and has special reference to that type of machine which will make bodies for paper receptacles similar to the type shown in my U. S. Letters Patent No. 890,985, dated June 16, 1908, and also for the manufacture of 20 the bodies of the paper receptacles as shown in my U. S. application Serial Number 852,635, filed July 23rd, 1914.

The object of this invention is to produce a machine which will automatically roll up, 25 paste and deliver a body of a paper receptacle.

Another object of this invention is to combine a multiplicity of independently operated machines into a single operated machine 30 so that a number of bodies for paper receptacles may be made simultaneously.

A further object of this invention is to simplify the construction of the machine for the manufacture of paper receptacles shown 35 in my U. S. Letters Patent Number 1,107,956 of August 18, 1914.

Other objects of this invention will appear in the specification hereinafter.

This invention consists in providing a series 40 of individual mandrels for rolling up blank sheets of paper into bodies of receptacles.

The invention further consists in providing a machine which employs vacuum means 45 for the manipulation of the paper sheets prior to and during the process of rolling said sheets into the bodies of receptacles.

This invention further consists in providing a series of sliding valves and sliding 50 valve mechanisms whereby certain conduits in the machine will have alternate communication with vacuum producing means and the open air.

In the drawings, Figure I, is a top plan 55 view of my invention showing the location of the several mandrels and their respective

arms and die plates and other co-acting parts. Two of the magazines for holding the supply of paper blanks are removed for the purpose of clearness.

Fig. II, is a cross sectional view taken through lines 2^a—2^a of Fig. I, and shows the construction of one arm and its co-acting parts, all of which are duplicated in each of the four arms shown.

Fig. III, is an end view partially in section, taken through lines 3^a—3^a of Fig. II, and shows the location of the mandrel and paste can after one revolution of the mandrel has been completed and also shows the 70 location of the blank sheets of paper in the magazine.

Fig. IV, is a sectional view taken through lines 4^a—4^a of Fig. II and shows the location of the several parts of the mandrel in relation to each other which are employed for the purpose of collapsing the mandrel to allow the finished body to be released therefrom.

Fig. V, is a sectional view taken through 80 lines 5^a—5^a of Fig. II and shows the construction of the rotary valve mechanism.

Fig. VI, is a side elevation view of the cam plate for operating the raising and lowering device of the suction tube.

Fig. VII, is a top sectional view taken through lines 7^a—7^a of Fig. II illustrating the construction of the sliding valve mechanism employed in the suction tube.

Fig. VIII, is a side elevation of the eccentric and concentric bolt, and

Fig. IX, is an isometric view of the collar and flange employed in the construction of the mandrel and will be more fully described hereinafter.

In constructing this machine I will employ a series of body making machines, each body making machine being similar to the machine described in my Patent Number 1,107,956. Revolvably mounted within the 100 base 1 is a shaft 2 which is provided with a hollow portion 3, which hollow portion 3 terminates at its lower end in the conduit 4. The upper end of the hollow portion 3 has permanent communication with the hollow portion 5 in each of the arms 6. As will be seen by referring to Figs. I and II, I prefer to form the arms 6, 6, 6, 6, in one piece and securely fastened to the revolvable shaft 2 by any suitable means such as a set 105 screw 7 and have so adjusted the arms that the hollow portions 5, 5, 5, and the hollow

portion 3, will at all times communicate with each other. Conveniently located on the shaft 2 I provide a beveled gear plate 8 having suitable teeth 9 which are adapted to be engaged by the teeth 10 of the intermittent gear 11, said gear 11 being driven by proper power applied to the shaft 12 mounted in the bearing 13. When the shaft 12 is revolved the gear 8 is accordingly revolved which in turn controls the movement of the shaft 2 and the arms 6, 6, 6, 6. On the outer end of each arm 6, I provide a combined concentric and eccentric bolt 14, (see Fig. VIII) upon the concentric portion 16 of which is hinged the bearing 15. On the eccentric portion 17 of said bolt 14 I hinge the flange 18 of the collar 19 by passing said eccentric portion 17 through the orifice 21 of the flange 18. At the inner end of the bearing 15 I have mounted the central portion 22 of the mandrel, which portion 22 revolves on said bearing 15 between the shoulder 23 and the flange 24 of the screw 25. On the central portion 22 of the mandrel I provide dove tails 26, 26, upon which are mounted the portions 27, 27 which complete the contour of the mandrel. At the end of each portion 27, and 27, I provide an extension 29 and 29 which extension is provided with inwardly extending flange 28, and 28, each of which are adapted to engage with and be retained in the groove 20 of the collar 19, (see Figs. IV and IX). The bearing 15 is provided with a hollow portion 30 which is provided with auxiliary conduits 31, 31, 31, 31, which in turn terminate at the outer surface of the reduced portion 37 of the bearing 15. The hollow portion 30 has communication with the conduit 33 which in turn is adapted to communicate with the hollow portion 5 of the arm 6 through the medium of the flexible tube 34 and the conduit 35. In the central portion 22 of the mandrel I provide an opening 36 which communicates with the reduced portions 37 thus a direct communication between the outer periphery of the mandrel and the conduit 4 is at all times provided.

The upper portion of the base 1 is formed into an enlarged head which is provided with projections 38, 38, 38, 38, which are formed hollow as at 39, 39, 39, 39; said hollow portions having communication with the hollow portion 40 which in turn has a direct communication with the conduit 41 leading to a vacuum producing means, such as a pump or other well known vacuum producing mechanism, not shown.

The shaft 2 is provided with an annular flange 42 through which the conduit 4 passes. This flange 42 revolves in the enlarged head above mentioned and the conduit 4 alternately communicates with the hollow portions 39, 39, 39, 39, and the spaces 43, 43, 43, 43, between the said projections 38, 38, 38,

and 38. The vacuum mechanism is continuously operated thus as the shaft and co-acting mechanisms revolve the mechanism causes the vacuum to first draw a sheet of paper from the die plate 45 to the mandrel 70 and then, after the said paper has been wound more than once around the said mandrel, the mechanism allows the entrance of air into the said mandrel thus releasing the grip of said paper caused by the vacuum. 75

Supported on the uprights 44, (see Fig. II) is a die plate 45 upon which the mandrel travels. For the purpose of strength I have provided a series of plates 46, 46, 46, 46, leading from said die plates 45, 45, to a bearing 47 through which the shaft 2 revolves. In the manner hereinbefore mentioned the mandrel is hinged to the arm 6. Securely mounted to the central portion 22 of the mandrel I have provided a gear wheel 48 cut out as at 49 to allow the flanges 28, 28 of the extensions 29, 29 to engage with the groove 20 of the collar 19. When the arm is carried forward (in the direction indicated by the arrow in Fig. I) the gear wheel 48 engages in the teeth of the rack 50 thus positively revolving the mandrel. When it is desired to form the bodies of the receptacle a blank sheet of paper 51 is placed on the die plate 45 in the manner hereinafter set forth. The mandrel being brought forward through the action of the arm 6 rolls from the portion 52 of the rack 50 and as it raises itself up to the surface of the die plate 45 the conduit 4 communicates with the space 39 thus allowing the vacuum to draw said sheet of paper 51 against the outer surface of the mandrel. The suction caused by the vacuum holds said sheet 51 against said mandrel until more than one 105 revolution of said mandrel has been completed at which time the conduit 4 communicates with the space 43 and allows the entrance of air and shuts off the suction caused by the vacuum hence the engagement between the paper blank 51 and the mandrel caused by the vacuum is released. A paste box 53 pivotally mounted to the arm 6 is so located as to precede the mandrel and is kept from engaging with the surface of the die 115 plate 45 by means of a spring 54 which tends to keep the paste box 53 and the supporting arm 55 suspended. The paste box 53 is carried by the rod 56 which in turn, is carried by the supporting arm 55. To the inner end 120 of the rod 56 is attached a roller 57 which is adapted to be engaged by the inclined strip 58 in such a manner that after one revolution of the mandrel has been completed the paste box 53 is brought downward thus allowing the roller 59 to engage with the remaining portion of the paper blank 51 and cover the same with an adhesive material. In order to positively revolve said roller 59 a gear wheel 60 is at 130

tached thereto and engages with the rack 50 while the roller 57 is engaged by the inclined strip 58. The mandrel is advanced from one end of said die plate 45 to the other and rolls said sheet of paper 51 a little more than twice around said mandrel, and at the end of said die plate 45 the mandrel pauses long enough to allow the paste or other adhesive material, which has been applied as above described, to firmly adhere to the body of the receptacle thus formed. After a predetermined pause, caused by the absence of the few teeth in the intermittent gear 11 the arm 6 is again advanced thus further advancing the mandrel. As the gear wheel 48 travels over the portion 52 of the rack 50 the mandrel being beyond the surface of the die plate 45 swings downwardly; the central portion 22 thereof hinged on the concentric portion 16 of the bolt 14 allows said portion 22 to swing on a perfect arc, the extent of the swinging being governed by the curve of the portion 52 of the rack 50. The dove tailed portions 27, 27, of the mandrel being connected as hereinbefore set forth to the collar 19 and the flange 18 are adapted to be forced downward in an arc beyond the arc of the central portion 22 thus diminishing the circumference of said mandrel as a whole and allowing the completed body portion of a receptacle to fall from said mandrel. Upon the further movement of the arm 6 and the hereinabove mentioned mandrel the dove tailed portions 27, 27, are returned to their original position and form the mandrel back into its normal contour ready for the rolling of another body of a receptacle on the next die plate 45. In order to provide a bearing for the inner end of the mandrel I have provided a lug 61 which engages in the portion 62 of the depending arm 63.

From the above it will be seen that I have described the operation of this machine as far as the manufacturing or forming of the body of a receptacle is concerned. I will now describe the operation and mechanism for automatically feeding the paper blanks 51 to the die plate 45, which is as follows:

Securely mounted to the shaft 2 is a horizontal disk 64 which is provided with a series of inclined lugs 65, 65, 65. As the shaft 2 revolves the disk 64 also revolves and the lugs 65, 65, 65 are so located that as the mandrel is leaving one die plate 45 after the body of a receptacle has been rolled up and pasted the said lugs 65, 65, 65 will act upon their respective lugs 66 on the inner end of the pivotally mounted arm 67 thus causing the outer end of the arm 67 to travel upward and carry therewith the tube 68. The arm 67 is pivotally mounted to the standard 86 as at 85. The lower end of the tube 68 is provided with a lug 69 to which is pivotally mounted a link 70 which in turn is pivotally mounted to the ex-

treme outer end of the arm 67. The upper end of said tube 68 is provided with a flexible air impervious tip 71 preferably flared as shown in Fig. II. The die plate 45 is provided with a countersunk orifice 72 through which passes the tube 68, and in which rests the tip 71, so that said tip 71 is level with or below the surface of the die plate 45. The tube 68 is provided with a hollow portion 73 which communicates with the tip 71 and which also communicates with an elongated orifice 74 in the side of the tube 68. On the under side of the die plate 45 I have mounted a hollow projection 75 in which the tube 68 operates. I provide an elongated orifice 76 on one side of said projection 75 in which the lug 69 travels. Approximately in line with or a little above the lower extremity of the hollow portion 73 of the tube 68 I provide an orifice 98 in the projection 75 which orifice 98 is adapted to communicate with the elongated orifice 74 in said tube 68 at predetermined times. At a point above the elongated orifice 74 I provide in the projection 75 an orifice 77 which communicates with a conduit 88 leading to a suitable vacuum producing medium, not shown. When the arm 67 is carried upward as hereinbefore mentioned the portion 99 of the tube 68 passes beyond the orifice 98 thus preventing the entrance of air into said tube 68. At approximately the same time the elongated orifice 74 is brought into communication with the orifice 77 which leads to the vacuum producing medium thus causing a suction to be created through the tube 68 and tip 71. This suction continues as the tube 68 travels upward. When the tube 68 travels far enough to allow the tip 71 to reach the lowest sheet 78 in the magazine 79 the lug 65 of the plate 64 passes over the lug 66 of the arm 67 thus allowing the tube 68 to drop to its original normal position. The suction through the tube 68 and the tip 71 causes the lowest sheet 78 to adhere to said tip 71 and thus the tube 68 coming back to its original position carries with it a blank sheet of paper 78 which takes the place of the sheet 51 on the die plate 45. In practice two tubes 68 and their co-acting parts may be employed for each die plate instead of one as shown, I having shown but one for the purpose of clearness. The magazine 79 is mounted to a standard 80 and is formed of such contour as to allow the blank sheets 81 to fit snugly therein. At each end of the magazine 79, the bottom of which is open, I provide a ledge 82 and in the middle of the outer wall of the magazine 79 I will provide a small lug 83; the ledges 82 and the lug 83 being employed to support the blank sheets 81 within the magazine 79. I also provide a weight 84 which fits loosely within the magazine 79 and tends to keep

the blank sheets 81 flat and compact within said magazine 79.

From the above description taken in connection with the drawings it will be clearly seen that I have provided a simple positively operated machine which will quickly manufacture the bodies of paper receptacles. As soon as one bottle body is completed the blank for another body is brought into position on each die plate, and the mandrels rolling from one plate to the other will form the bottle bodies very rapidly.

I have also provided sliding and rotary valves for the vacuum operating mechanisms wherein communication is made with vacuum producing means and air, alternately as desired.

In setting forth and describing this invention I have shown the same as it appears best adapted but it is apparent that many minor changes of construction may be necessary or convenient hence I do not wish to be limited to the details of construction as modifications may be made without departing from the invention.

Having thus described my invention, what I wish to claim is:

1. A machine for the manufacture of paper receptacles comprising a die plate, a mandrel adapted to be rolled upon said die plate to form a body of a paper receptacle, a bearing upon which said mandrel is mounted, a revolvably mounted standard, an arm carried thereby, said bearing being adjustably attached to said arm, in combination with conduits leading from the outer surface of said mandrel to said standard, and means in combination with said standard for alternately directing said conduits to vacuum producing means and to air.

2. A machine for the manufacture of paper receptacles, comprising a standard, an arm revolvably mounted thereon, a mandrel rotatably mounted on said arm, a die plate upon which said die mandrel rolls, a valve carried by the standard and operated by the revolution of the arm, a vacuum passage connected with the valve, conduits leading from the outer surface of said mandrel to said valve, said valve being adapted to direct said conduits alternately to the vacuum passage and to the outside air.

3. In a machine for manufacturing paper receptacles, the combination of a series of individually operated mandrels, a series of die plates, means for causing the mandrels to move successively over the die plates, means for automatically feeding blanks to the die

plates in advance of each mandrel, means for causing the blanks to be rolled onto the mandrel, and means for removing the receptacles from the mandrels between the die plates.

4. In a machine for manufacturing paper receptacles, the combination of a die plate, a mandrel adapted to be rolled upon the die plate to form the body of the receptacle, a magazine for positioning body blanks opposite the die plate, a slideable member extending through said die plate and adapted to engage a blank in the magazine and draw it to the die plate in advance of the mandrel.

5. In a machine for the manufacture of paper receptacles, the combination of a die plate, a mandrel adapted to roll on the same to form the body of a receptacle, a magazine for the blanks from which the bodies are formed opposite the die plate, a tube extending through the die plate, means for applying suction thereto, and means for moving the tube to the magazine to withdraw the adjacent blank and position it on the mandrel.

6. In a machine for manufacturing paper receptacles, the combination of an arcuate platen, means for moving a mandrel over the same, a magazine above the platen adapted to expose the lowermost of a series of blanks for the bodies of the receptacles, tubes extending through the platen at separated points, and means for moving the tubes upwardly to engage the lowermost blank, and means for applying suction thereto, whereby when the tubes are withdrawn the blank is positioned on the platen.

7. In a machine for manufacturing paper receptacles, the combination of a platen, a mandrel moving over the same, carrying means for the mandrel, a magazine opposite the platen, a tube extending through the platen and adapted to be reciprocated to the nearest blank in the magazine and carry a blank back to the platen, tubular passages leading from the periphery of the mandrel through its carrying members, and means for applying suction to each of said passages for causing each mandrel to seize a blank upon the platen and cause it to adhere to the mandrel.

Signed at Cleveland in the county of Cuyahoga and State of Ohio this 15th day of March 1915.

DAVID J. JENNINGS.
